JOSEPH J. SMITH, OF DEEP RIVER, CONNECTICUT

TOOL

Application filed January 31, 1930. Serial No. 425,036.

This invention relates to tools.

It is among the objects of the present invention to provide a novel and improved driving tool adapted for use in conjunction with pneumatic hammers.

It is a further object of the present invention to provide a removable driving head for pneumatic hammers, which is particularly adapted to drive nails.

10 A further object of the present invention is to provide a driving tool for pneumatic hammers which is adapted to drive nails and which is further adapted for use in setting the nail head below the surface of the material into which the nail is being driven.

Other objects of the present invention include the novel construction and interrelation of parts whereby a simple and improved adjustable pneumatic hammer head is provided.

20 Other objects of the present invention will be apparent from a consideration of the following specification taken in conjunction with the accompanying drawing, in which

Figure 1 is a side elevation of one form of the present invention;

Fig. 2 is a sectional view taken on the line 2—2 of Fig. 1;

Fig. 3 is a transverse section taken on the line 3—3 of Fig. 2.

30 Referring more particularly to the drawing, the present invention includes a longitudinal shaft 10, one end of which is adapted to be provided with a suitable head (not shown) which is adapted to be received within a conventional form of pneumatic driving mechanism, such as the pneumatic hammer now in use. No specific type of connecting head is provided on the shaft 10, it being understood that this forms no part of the present invention, and that any preferred type of connecting head may be used, if desired.

The shaft intermediate its ends is provided with an extending shoulder 11, and at its 45 lower end is reduced to provide a driving terminal 12. As shown in the drawing, the shaft 10 including the shoulder 11 and terminal 12, is preferably formed integral. It is within the scope of the invention, however, 50 to form the shaft assembly of various parts

should structural or manufacturing advantages be obtained thereby.

Slidably mounted upon the shaft 10, a housing 13 is provided. The housing 13 has a central bore adapted to receive the shaft 10 below the shoulder 11, the bore at the end of the housing being reduced as at 14, to guide the reduced driving extremity 12. The upper end of the bore of the housing 13 is enlarged, as at 15, to receive therein a coil spring 15a, surrounding the shaft 10, the upper end of the spring abutting the lower face of the shoulder 11, while the lower end of the spring abuts the end of the enlarged portion 15 of the housing bore. The arrangement is such that the expansion of the spring normally tends to force the housing 13 downwardly with respect to the shaft 10, whereby the driving portion 12 is normally received within the confines of the housing.

For securing the housing for movement over the shaft 10, a split shackle 16 is provided, the halves of which are adapted to be bolted together by bolts 17. The upper end of the shackle extends inwardly to be received over the upper face of the shoulder 11, while the lower end of the shackle extend inwardly as at 18, to be received within a recess in the upper end of the outer surface of the housing 13, the arrangement being such that free upward movement of the shackle and housing with respect to the shoulder 11 is provided, while the shoulder 11 acts to limit the downward movement of the housing under the influence of the spring.

The structure is completed by the provision of apertures 19 in the housing 13, which lead into the bore of the housing, whereby lubrication between the housing and shaft may be applied. Lubricating and cleaning apertures 20 are also provided in the tapered lower extremity of the housing. The lower end of the housing is provided with a countersunk recess 21 terminating the reduced bore 14 of the housing. The co-operation of this configuration together with the apertures 20, provides for the cleaning of the lower extremity and for lubrication thereof.

In the operation of the device, the head of a nail or the like may be received within the

conical recess of the lower end of the housing. The driving tool associated with the upper end of the shaft 10 is then operated and the shaft reciprocates within the housing 13. 5 During such reciprocation it will be seen that the driving extremity 12 moves within the bore 14 to drive the nail, the relative movement of the housing 13 in the shaft being such that the extremity 12 preferably extends 10 from the housing 13 when in its lowest position with respect thereto.

With this construction it will be seen that when a nail is driven with its head flush to the working surface, the housing 13 may be 15 held against the working surface and the reciprocation in the shaft therein will drive the head of the nail below the working surface, thus to effect a setting operation.

From the foregoing it will be understood 20 that the invention is not confined to the specific structural details herein shown, but that numerous changes, modifications, and the full use of equivalents may be resorted to without departing from the spirit or scope of 25 the invention as outlined in the appended claims.

What is claimed is:

1. A nail guiding, setting and impact transmitting device including a tubular casing having an external annular groove adjacent one of its ends, an impact shaft mounted therein for guided axial movement, having one end constantly projecting from the casing and the other end normally retracted 30 within the casing, a circumferential enlargement formed on said impact shaft and a member having mating sections clampingly engaging the end of the casing through which the shaft constantly projects, said sections 35 formed with inwardly projecting annular ribs fitting within said casing groove, and an inwardly projecting shoulder formed on said sections for cooperation with the upper end of the enlargement to limit the outward movement of the impact shaft from the casing.

2. In a device of the character set forth, a tubular casing having an upper bore, an intermediate bore of lesser diameter than the 50 upper bore and a lower bore of lesser diameter than the intermediate bore, said bores defining at their juncture upper and lower shoulders within the casing, an impact shaft extending axially through the casing and having its major length of a diameter corresponding to that of the intermediate casing bore, said shaft having a circumferential enlargement of a diameter corresponding to the upper bore and a reduced lower terminal corresponding to the diameter of the lowermost 55 casing bore, a coiled expansion spring surrounding the shaft and interposed between said enlargement and the uppermost shoulder and a pair of mating semi-cylindrical sections secured to and projecting beyond the 60

upper end of the casing and formed with marginal inwardly offset upper ends combining to provide an annular shoulder for limiting relative movement of the casing and impact shaft and for guiding the upper end of 70 said impact shaft.
